DECORATIVE PICK FOR ATTACHMENT OF
FLOWERS TO A BASE MATERIAL

Saul Klayman, Mattapan, Mass., assignor to Kandy-Pak,
Inc., Roslindale, Mass.

Filed Aug. 23, 1968, Ser. No. 13,253

Term of patent 14 years

Int. Cl. D8—01

U.S. Cl. D35—1

FIG. 1 is a perspective view of the decorative pick for attachment of flowers to a base material embodying my new design;

FIG. 2 is an end elevational view thereof;

FIG. 3 is a side elevational view thereof;

FIG. 4 is an elevational view of another side thereof;
and

FIG. 5 is a perspective view in detail of a portion thereof.

The broken line representation of the flower and base material in FIG. 1 is for purposes of illustration only.

I claim:

The ornamental design for a decorative pick for attachment of flowers to a base material, substantially as shown and described.
